Filed Mar. 31, 1960, Ser. No. 59,969

Term of patent 7 years

(Cl. D1—12)

FIG. 3

FIG. 1

FIG. 2

FIGURE 1 is a front elevation of the combined clock and illuminable advertising sign or the like, showing my new design, the rear being substantially plain;

FIG. 2 is a top plan view thereof, the bottom being substantially plain; and

FIG. 3 is a side elevational view thereof on a reduced scale.

The stippled shading in FIG. 1 indicates contrasting surface areas.

I claim:

The ornamental design for a combined clock and illuminable advertising sign or the like, as shown and described.
